UNITED STATES PATENT OFFICE.

ADOLPH LUND, OF CHICAGO, ILLINOIS.

FLOOR AND CEILING CONSTRUCTION.

SPECIFICATION forming part of Letters Patent No. 611,366, dated September 27, 1898.

Application filed December 10, 1897. Serial No. 661,356. (No model.)

To all whom it may concern:

Be it known that I, ADOLPH LUND, a citizen of the United States of America, residing at Chicago, in the county of Cook and State of Illinois, have invented certain new and useful Improvements in Floor and Ceiling Constructions, of which the following is a specification.

My invention relates to floor and ceiling constructions, the object of which is to provide means for supporting an arched floor upon a series of parallel joists or floor-beams and in connection therewith to provide simple and economical means for supporting a ceiling beneath such a floor.

To such end the invention consists in certain novel means for the purpose stated, which will be fully described below in their preferred form and the essential features thereof pointed out in the appended claims.

In the drawings presented herewith, Figure 1 is a perspective of a complete floor-section. Fig. 2 is a perspective of a stirrup adapted to support the adjacent ends of two arches and to embrace one of the flooring-strips. Fig. 3 is a perspective of one of the floor-beams and certain modified forms of stirrups applied thereto. Figs. 4 and 5 are perspectives of other modifications of the stirrups; and Fig. 6 is a perspective of a floor-beam and another form of stirrup, showing in connection therewith means for supporting the ceiling-strips.

Looking first at Fig. 1, A A' are two I-beams used as joists or floor-beams. B B are flooring-strips. C C are ceiling-strips. D D are arches, shown as of corrugated iron, and E is a suitable filling between the arches and the flooring. Upon the tops of the floor-beams are hung a series of stirrups F, which extend across the top of the beams, down upon the opposite sides, and then outward from the beams, forming brackets f, the ends of which abut against the beams and which furnish a support for angle-irons H, upon which rest the ends of the arches D. The thrust of said arches is thereby brought directly against the beams, and said beams are sustained against said thrust by the adjacent arch upon the other side. In this view, Fig. 1, a modified form of stirrup G (shown on a larger scale in Fig. 4) is used to secure the flooring-strips B to the I-beams, said stirrup having upturned

edges g, perforated so that they may be nailed to the edges of the flooring-strips, and downturned sides g' g'', the side g'' being also turned in to embrace the upper flange of the floor-beam and the other side being perforated to receive the loop of a wire c, (see Fig. 1,) which carries, by means of a loop at its other end, one of the ceiling-strips C.

Fig. 2 shows a modified form of stirrup F', similar to that shown at F, with the exception that the ends f' are turned upward to receive one of the flooring-strips and the brackets f are perforated to hold one of the ceiling-supporting wires c.

Fig. 6 shows another modification, F'', of said stirrup F, similar to that shown in Fig. 2, omitting, however, the upturned ends f'.

Fig. 3 shows at F''' another modification of the stirrup F, adapted to a channel-iron, the difference being that one of the downturned portions makes a right angle with the horizontal portion to fit the square corner of the channel-iron. Said figure also shows at F'' a modification of the stirrup F'', (seen in Fig. 6,) the difference being that one of the downturned portions f'' makes a right angle with the horizontal portion and the laterally-extending bracket f''' extending outward from said portion has a tongue f'' cut from it and extended directly downward from the portion f'' and perforated to receive one of the ceiling-supporting wires c.

In Fig. 5 a bracket F'' is seen adapted to support the adjacent ends of two arch-bars when the nature of the floor construction makes it desirable to use such bars. In this case the brackets f'' are formed into sockets fitted to receive the ends of the arch-bars.

I am aware that still further variation in the form of construction of the various parts of my invention is possible; but I deem those already shown sufficient to illustrate the nature of the invention and the essential features thereof.

I claim as new and desire to secure by Letters Patent—

1. The combination with a series of floor-beams, of a series of stirrups resting upon the tops of said beams and having depending portions extending downward along the sides thereof and projecting outward at the bottom to furnish supporting-brackets for floor-

arches, the depending portions being adapted to rest directly against the beams so as to transmit the lateral thrust of the arches thereto; substantially as described.

5 2. The combination with a series of floor-beams and a series of floor-strips, of a series of stirrups resting upon the floor-beams having upturned portions adapted to hold the floor-strips in place and downturned portions resting directly against the beams and having outwardly-extending ends adapted to support a series of arches; substantially as described.

15 3. The combination with a series of floor-beams, a series of floor-strips resting thereon and a series of ceiling-strips supported thereby, of a series of stirrups resting on the beams having upturned portions adapted to hold the flooring-strips in place and downturned portions provided with means for supporting the ceiling-strips, substantially as described.

4. The combination with a series of floor-beams and a series of ceiling-strips supported therefrom, of a series of stirrups resting upon 25 the floor-beams and having depending portions extending downward along the beams and projecting outward at the bottom to provide a bracket for the support of floor-arches, said depending portions of the stirrups resting against the beams to transmit the thrust of the arches thereto and being provided with suitable devices for supporting the ceiling-strips; substantially as described.

30 5. A bracket for the support of floor-arches upon flanged iron floor-beams consisting of a stirrup adapted to rest upon the top of one

of the beams and having depending portions extending downward and inward sufficiently to rest against the web of the beam, said depending portions having outwardly-projecting shoulders upon which the arches may rest; substantially as described. 40

6. The combination with a series of floor-beams, of a series of stirrups resting thereon having depending portions extending downward against the beams and outward at the bottom, a series of angle-irons resting upon these outwardly-extending portions and a series of arches resting upon the angle-irons; substantially as described. 45

7. The combination with a series of floor-beams, a series of flooring-strips and a series of ceiling-strips, of stirrups resting upon the floor-beams having depending portions extending downwardly and outwardly at the bottom and resting against the beams, a series of angle-irons upon the outwardly-extending portions, a series of arches resting upon the angle-irons, and a series of stirrups resting upon the floor-beams, having upturned 55 portions holding the floor-strips in place and downturned portions connected with and holding the ceiling-strips; substantially as described.

In witness whereof I have hereunto set my hand, at Chicago, in the county of Cook and State of Illinois, this 29th day of November, A. D. 1897.

ADOLPH LUND.

Witnesses:

CHAS. O. SHERVEY,
A. I. H. NELSON.
